UNITED STATES PATENT OFFICE

CLARENCE G. SNOOK, OF TROY, OHIO, ASSIGNOR TO THE TROY SUNSHADE COMPANY, OF TROY, OHIO, A CORPORATION OF OHIO

ARTICLE OF FURNITURE

Application filed August 20, 1927. Serial No. 214,315.

This invention relates to an article of furniture, such as a couch hammock.

One of the principal objects of the invention is to provide an article of furniture having readily detachable and reversible 5 cushions.

Another object of the invention is to provide an article of furniture having cushions with different designs or color schemes on 10 opposite sides or faces thereof, so that the cushions may be used with the faces having the preferred design or color scheme exposed.

Still another object of the invention is to provide a cushion having means for detachably and reversibly connecting the same to the seat frame of an article of furniture, the connecting means being simple in construction, inconspicuous, readily detachable, and sturdy to insure long life.

Other objects and advantages of the invention will be apparent from the following description when taken in connection with the accompanying drawing and appended claims.

In the drawing in which like characters of reference designate like parts throughout the several views thereof;

Fig. 1 is an elevational view, somewhat in the nature of a perspective, of a couch hammock constructed in accordance with this invention;

Fig. 2 is an end elevational view of the couch hammock of Fig. 1;

Fig. 3 is a fragmentary sectional view 35 through the seat frame on the plane of the line 3—3 of Fig. 4 showing a back cushion in end elevation to illustrate the reversible connection between the back cushion and the seat frame;

Figure 4 is a fragmentary plan view of the seat frame and back cushions to further illustrate the reversible connection of Fig. 3; and

Fig. 5 is a front elevational view of a seat cushion illustrating the connection of the depending skirt to permit reversal of the seat cushion.

Referring to the drawing, in which a preferred embodiment of the invention is illustrated, there is disclosed a couch ham-

mock comprising a swingable seat frame suspended from suitable supports to give a pleasing swinging motion. The seat frame includes a base frame 10, and a back 11 suitably connected together. Any conventional construction of the seat frame may be used, and consequently this part is not illustrated in more detail. The seat frame is also provided with arms 12 at each end thereof, each arm being suitably connected with the back frame and with the base frame. For supporting the seat frame for swinging movement, standards 13 are provided at each end of the couch hammock, each standard having a supporting base 15 resting upon the floor. A cross bar 19 connects the two standards, the cross bar extending beneath the swingable seat frame. The upper end of each standard is provided with a hook 14 to which is attached supporting chains 16 fastened to the rear and front ends of an arm 12 respectively. The supporting chains preferably include as elements coiled springs 17. The arms 12 are preferably provided with hooks 18, one end of each spring 17 being fastened in the corresponding hook 18 and the other end of the spring 17 being connected to the chain 16.

The seat is provided with back cushions 20 and seat cushions 21. Each of the back cushions 20 is provided with means for detachably connecting it to the back of the seat frame to support the cushion in position, this means being constructed to permit the cushion to be readily detached, reversed, and again connected to the seat frame with the opposite face thereof exposed.

For this purpose, the back of the seat frame is provided with a plurality of attaching members 24, each attaching member being shown as an angle piece having a back face 25 provided with holes therethrough adapted to receive attaching means such as screws 26 for rigidly fastening the member to the seat frame, and an attaching face 27 disposed at right-angles to the back face and extending forwardly from the back of the seat frame. This attaching face 27 is provided with openings as indicated at 28, adapted to receive the connecting means fastened to the cushion 100

to detachably connect the cushion to the seat frame.

Each back cushion is provided with connecting means at each side thereof in order to securely support the cushion in position. The form of connecting means shown is flexibly and movably fastened to the cushion in order to permit the connecting means to be swung to positions such that the cushion may be connected to the seat frame with either face exposed. As shown, each connecting means comprises a hook member 30 one end 31 thereof being adapted to pass through an opening 28 within an associated attaching member to detachably connect the cushion to the seat frame. The other end of the hook member is in the form of a loop 32, which receives a flexible strap 34 formed of any suitable flexible material such as cloth. The ends 20 of the strap are brought together and sewed or otherwise attached to the cushion. As shown the cushion is made of two similar parts sewed together to form a seam 35 substantially midway between the front and rear faces of the cushion. Where this form of cushion is used, the ends of the straps 34 are sewed within this seam at the time the cushion cover is made. The hooks 30 are freely movable within the loops of the strap 34, so that the hook can be swung to either side of this connection so as to be disposed substantially parallel with the side of the cushion. Thus when the cushion is reversed it is only necessary to remove the hook from the attaching member, reverse the cushion, swing the hook to the opposite side of its point of connection with the cushion, and insert the hook within the attaching member.

A single attaching member may be used between two adjacent cushions to detachably receive the hook means of both cushions. Thus as shown clearly in Fig. 4, the attaching face 27 of the attaching member is provided with two openings 28 adapted to receive respectively the hook members of the two adjacent cushions. In that case four attaching members, one at each end of the couch hammock and two at intermediate points between the cushions, serve to fasten the three back cushions to the seat frame. Preferably the side edges of the attaching face 27 are curved to permit the cushions to be disposed snugly against each other and to prevent injury to the cushions which might result from a sharp edge formed on the attaching member. With the cushions in position, it is seen that the detachable connecting means are quite inconspicuous, if not entirely hidden.

Each seat cushion 21 is also made readily reversible, but fastening means is not needed to hold them in position. In order to present a pleasing appearance to the couch hammock, each seat cushion is provided with a depending skirt 40. As shown particularly

in Fig. 5, this skirt is attached substantially centrally of the front end face of the seat cushion. Thus the skirt maintains substantially its same relative position with respect to the seat cushion irrespective of which horizontal face of the seat cushion is uppermost or exposed. The seat cushion may be reversed by simply turning the cushion over so as to maintain the front end face at the front of the couch hammock, and in the reverse position the skirt 40 will hang downwardly the same length to give substantially the same pleasing appearance as in its former position.

The cushions may have the same design or color scheme on the opposite face thereof, if desired, and may be reversed when one side becomes soiled or for other reasons. Preferably, the opposite faces of the cushions are provided with different designs or color schemes so that the couch hammock may be given quite a changed appearance by simply reversing the cushions. Thus as indicated in Fig. 3, the face 42 of the cushion which in the position shown is at the front and exposed is shaded to denote one color or design, while the face 43 of the cushion which is at the rear adjacent the seat frame is differently shaded to denote a different color or design.

Similarly the opposite sides of the skirt 40 may have different designs or color schemes to correspond with the designs or color schemes of the faces of the cushions. Thus as indicated in Fig. 5, wherein one corner of the skirt 40 is shown as upturned for purposes of illustration, the front side 45 of the skirt is shaded to denote one color or design which corresponds with the color or design of the front face 42 of the rear cushion, while the rear side 46 of the skirt is differently shaded to denote a different color or design which corresponds with the color or design of the face 43 of the rear cushion.

When the cushions and skirts are thus given different designs, the upper half or portion 48 of the front end of each cushion is given the design or color corresponding to the color of the upper face of the cushion and the exposed side of the depending skirt, while the lower half or portion 49 of the front end of the cushion is given a different design to correspond with the bottom face of the cushion and the rear side of the depending skirt. Thus when the seat cushion is reversed, the exposed portions of the cushion and skirt correspond in design or color scheme.

While this invention is described as being applied to a couch hammock, it is to be understood that the invention is applicable to other types of furniture wherein detachable and reversible cushions may be used.

While the form of apparatus herein described constitutes a preferred embodiment of the invention, it is to be understood that the invention is not limited to this precise form of apparatus, and that changes may be made

therein without departing from the scope of the invention which is defined in the appended claims.

What is claimed is:

- 5 1. As an article of manufacture, a cushion for a seat frame of an article of furniture, said cushion having a side wall and a seam arranged substantially centrally of the said side wall, a detachable connecting means, flexible means distinct from the cushion fastened to said cushion within said seam and attached to said connecting means on the exterior of the cushion to permit said cushion to be detachably and reversibly connected to said seat frame.
- 10 2. As an article of manufacture, a cushion for a seat frame of an article of furniture, said cushion having a seam arranged substantially centrally of an end face thereof, hook means for detachably and reversibly connecting said cushion to said seat frame, said hook means having a substantially closed loop, and a strap positioned within said loop, the ends of said strap being sewed within said seam.
- 15 23 In testimony whereof I hereto affix my signature.

CLARENCE G. SNOOK.
